(21) Appl. No.: **29/406,878**

(57) CLAIM

(22) Filed: **Nov. 21, 2011**

I claim the ornamental design for a packaging box for confectionery, as shown.

(30) **Foreign Application Priority Data**

DESCRIPTION

Sep. 19, 2011 (KR) 30-2011-0038868

The file of this patent contains at least one drawing or photograph executed in color. Copies of this patent with color drawing(s) or photograph(s) will be provided by the Patent and Trademark Office upon request and payment of necessary fee.

(51) **LOC (9) Cl.** **09-01**

FIG. 1 is a perspective view of a packaging box for confectionery showing our new design;

(52) **U.S. Cl.** **D9/622; D9/643; D9/418; D9/432**

FIG. 2 is a front-side elevational view thereof;

(58) **Field of Classification Search** D7/514-515,

FIG. 3 is a rear-side elevational view thereof;

D7/606, 613, 628; D9/600, 614-623, 643,

FIG. 4 is a left-side elevational view thereof;

D9/414, 418, 430-433; 206/457, 527, 540;

FIG. 5 is a right-side elevational view thereof;

220/890

FIG. 6 is a top view thereof; and,

See application file for complete search history.

FIG. 7 is a bottom view thereof.
